(57) **CLAIM**

The ornamental design for a paper towel dispenser, as shown and described.

DESCRIPTION

FIG. 1 is a front, right side and top perspective view of a first embodiment of a paper towel dispenser showing my new design;

FIG. 2 is a front elevational view thereof;

FIG. 3 is a left side elevational view thereof, the right side elevational view being a mirror image thereof;

FIG. 4 is a top plan view thereof;

FIG. 5 is a bottom plan view thereof;

FIG. 6 is a rear elevational view thereof;

FIG. 7 is a front, right side and top perspective view of a second embodiment of a paper towel dispenser showing my new design;

FIG. 8 is a front elevational view thereof;

FIG. 9 is a left side elevational view thereof, the right side elevational view being a mirror image thereof;

FIG. 10 is a top plan view thereof;

FIG. 11 is a bottom plan view thereof;

FIG. 12 is a rear elevational view thereof;

FIG. 13 is a front, right side and top perspective view of a third embodiment of a paper towel dispenser showing my new design;

FIG. 14 is a front elevational view thereof;

FIG. 15 is a left side elevational view thereof, the right side elevational view being a mirror image thereof;

FIG. 16 is a top plan view thereof;

FIG. 17 is a bottom plan view thereof;

FIG. 18 is a rear elevational view thereof;

FIG. 19 is a front, right side and top perspective view of a fourth embodiment of a paper towel dispenser showing my new design;

FIG. 20 is a front elevational view thereof;

FIG. 21 is a left side elevational view thereof, the right side elevational view being a mirror image thereof;

FIG. 22 is a top plan view thereof;

FIG. 23 is a bottom plan view thereof; and,

FIG. 24 is a rear elevational view thereof.

The oblique lining in the drawings represents a frosted translucent material.

The broken line showing is included for the purpose of illustrating only and forms no part of the claimed design.
